[57] CLAIM

The ornamental design for an electronic clinical thermometer, as shown and described.

DESCRIPTION

FIG. 1 is a top, front, and right side perspective view of an electronic clinical thermometer showing my new design;

FIG. 2 is a right side elevational view;

FIG. 3 is a left side elevational view;

FIG. 4 is a rear elevational view;

FIG. 5 is a front elevational view;

FIG. 6 is a top plan view;

FIG. 7 is a bottom plan view;

FIG. 8 is a cross-sectional view as taken from line VIII—VIII of FIG. 2; and

FIG. 9 is a cross-sectional view as taken from line IX—IX of FIG. 5.

FIG. 1

FIG. 2

FIG. 3

FIG. 4

FIG. 5

FIG.7

FIG.9
